UNITED STATES PATENT OFFICE

2,542,316

ARTIFICIAL LIMB

William G. Farrar, Jr., Ottawa, Ill.

Application December 23, 1946, Serial No. 718,076

5 Claims. (Cl. 3—12)

1

The present invention relates to new and useful improvements in artificial limbs and more particularly to an artificial hand and wrist.

An important object of the invention is to provide an artificial limb of this character that has a natural appearance and which yields to the grip of others to provide the effect of a normal hand.

A further object of the invention is to provide means controlled by the movement of the arm of a person to open and close the fingers of the artificial hand.

An additional object is to provide a universal movement for the wrist portion of the artificial limb.

A still further object is to provide an artificial hand and wrist including a rigid skeleton frame for the hand encased in resilient material such as rubber or the like which will yield to the touch and also providing means for normally maintaining the artificial hand in an extended position and operable to close the fingers by a predetermined movement of the arm to which the artificial hand is attached.

Another object is to provide a device of this character of simple and practical construction, which is neat and attractive in appearance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a front elevational view of the artificial limb and showing the harness attached in position to the arm of a person.

Figure 2 is an enlarged sectional view of the hand and wrist of the artificial limb.

Figure 3 is a sectional view taken on a line 3—3 of Figure 2.

Figure 4 is a group perspective view of one of the finger joints.

Figure 5 is an elevational view of the outer joint of one of the fingers and showing the artificial finger nail in position thereon.

Figure 6 is a perspective view of the artificial finger nail removed from the finger, and

Figures 7, 8 and 9 are transverse sectional views taken respectively on lines 7—7, 8—8 and 9—9 of Figure 2.

Referring now to the drawings in detail wherein for the purpose of illustration I have dis-

2

closed a preferred embodiment of the invention the numeral 5 designates a rigid skeleton frame for an artificial hand and which is preferably constructed of light weight metal, the side edges of the frame being curved inwardly as shown at 6 to provide a desired thickness therefor. The frame 5 is enclosed in a covering of molded material 7, such as flexible rubber or other suitable material having comparatively little porosity, the covering being shaped into the form of an artificial hand to include the fingers 8 and thumb 9.

Each of the fingers 8 and thumb 9 is provided with a reinforcing core designated generally at 10 embedded therein, the cores for the several fingers being of identical construction and accordingly a detailed explanation of one will suffice for all. Each of the cores includes inner and outer phalanges 11 and 12 and an intermediate phalange 13 representing the several phalanges of the finger. The inner phalange 11 is formed with eyes 14 and 15 and at its ends, the eye 14 being aligned with an eye 16, the latter being formed with a bifurcated extension 17 welded or otherwise suitably secured to an edge of the frame 5. The aligned eyes 14 and 16 are pivoted to each other by means of a pin 18. The eye 14 is formed with a rearwardly extending stop 19 engaging a stop 20 on the eye 16 to prevent backward pivotal movement of the finger at the inner or knuckle phalange 11.

The intermediate phalange 13 is likewise formed at its ends with eyes 21 and 22, the eye 22 being aligned with the eye 15 and pivoted thereto by a pin 23. The eye 22 is likewise formed with a stop 24 and the eye 15 is also formed with a stop 25 cooperating to prevent backward pivotal movement of the phalange 13.

The inner end of the phalange 12 is formed with an eye 26 aligned with the eye 21 of the intermediate phalange 13 and pivoted thereto with a pin 27 and the eyes 21 and 26 are also formed with stops 27' and 28.

The frame 5 adjacent each knuckle phalange is provided with a pin 29 and laterally projecting pins 30 are also provided adjacent each end of the phalanges 11 and 13 and at the inner end of the phalange 12, the pins having coil springs 31 attached thereto for connecting the several phalanges to each other at their pivoted ends and for connecting the inner phalange 11 to the frame, the springs being arranged to maintain the cores in an extended position and to thus straighten the fingers 8.

The core for the thumb 9 is similarly con-

structed except that only two phalanges are provided for the thumb, namely the inner phalange 32 and the outer phalange 33, otherwise the construction of the core for the thumb is similar to that provided for the fingers as heretofore described.

The front edge of each of the phalanges for the fingers and thumb is provided with guides 34 through which a flexible wire 35 is slidably received, such as piano wire, the end of the wire being attached in any suitable manner to a lug 36 adjacent the outer ends of the outer phalanges 12. The wires 35 for the several fingers extend to guides 37 suitably secured to the front surface of the frame 5 and all of the wires extend through a guide tube 38 secured to the frame 5 and extending outwardly through the wrist portion 39 of the hand on the inside of the wrist as shown in Figure 1.

The wires 35 then extend rearwardly through a guide 40 carried by a forearm strap or harness 41 and the rear ends of the wires are then attached to a plate 42 carried by a strap or harness 43 secured to the upper arm of a person. The coil springs 44 are interposed in the several wires adjacent their inner ends.

The resilient wrist portion 39 is of tubular construction and telescopes over a rigid socket 45 in which the stump of the forearm is received and secured in position by the harness 41.

The outer end of the socket 45 is formed with a bracket 46 having a pair of aligned eyes 47 and in which the smooth ended pins or bolts 48 are threaded, the inner ends of the pins having the opposite edges of a plate 49 pivotally attached thereto. The plate 49 is provided with a pin or rivet 50 extending therethrough at right angles to the pins 48 and on the ends of which a yoke 51 is pivotally mounted, the yoke projecting rearwardly from the inner edge of the frame 5. The pins 48 and 50 thus provide a universal connection at the wrist portion 39 of the artificial limb to thus enable movement of the hand from side to side or forwardly and rearwardly.

Coil springs 52 extend longitudinally into wrist portion 39 and connect the inner ends of the frame 5 at the front, rear and side portions thereof to corresponding portions of the socket 45, the springs exerting their influence on the hand to normally maintain the same in an extended position at the outer end of the socket 45.

Each finger and thumb is provided with an artificial fingernail 53 formed with a flange 54 at its edges for removable insertion in recesses 55 at the tips of the fingers and thumb, the nails being colored to simulate natural finger nails. The finger nails are removable for cleaning, when desired.

In the operation of the device with the wrist 39 attached to the socket 45 as indicated and the socket secured to the stump of a forearm as shown in Figure 3 the flexible covering 1 for the hand and wrist will enable the springs 31 at the several phalanges of the fingers and thumb to maintain the fingers and thumb in an extended position when the arm of the person is bent at the elbow. However upon straightening of the arm at the elbow a pulling action will be imparted to the wires 35 leading to the outer phalanges of the fingers and thumb thereby causing the fingers and thumb to close inwardly against the palm of the hand as shown in Figure 1 of the drawings and the fingers and thumb may then be used to grip an object to be carried by the artificial hand.

The universal joint at the wrist of the artificial limb will enable the hand to flex from side to side or forwardly and backwardly when the hand is subjected to lateral pressure.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

I claim:

1. An artificial hand comprising a hand portion and a wrist portion, said hand portion including a rigid skeleton frame and said wrist portion including a rigid socket for receiving the stump of a forearm, a covering of yieldable material enclosing said frame and socket, a universal spring biased connection between the frame and the socket normally supporting the hand in an extended position, said hand also including bendable fingers which are solid except for relatively small irregularly shaped bores therein, jointed cores for the bores in said fingers, and flexible means extending rearwardly from the outer ends of the cores and connected to a person's arm above the elbow and operable to close and to open the fingers upon a flexing of the arm at the elbow.

2. An artificial hand comprising a hand portion and a wrist portion, said hand portion including a rigid skeleton frame and said wrist portion including a rigid socket for receiving the stump of a forearm, a covering of yieldable material enclosing said frame and socket, a universal spring biased connection between the frame and the socket normally supporting the hand in an extended position, said hand also including bendable fingers which are solid except for relatively small irregularly shaped bores therein, jointed cores for the bores in said fingers, means pivotally connecting the inner ends of the cores to the frame, and flexible means extending rearwardly from the outer ends of the cores and connected to a person's arm above the elbow and operable to close and to open the fingers upon a flexing of the arm at the elbow.

3. In an artificial limb wrist and hand portions, said wrist portion including a rigid socket and said hand portion including a rigid skeleton frame, a bracket at the outer end of said socket having spaced apart aligned eyes, a pivot connecting the plate to the eyes at its opposite side edges, a yoke extending inwardly from the skeleton frame of the hand portion and straddling the plate, and a pivot connecting the yoke to the plate, said first and last named pivots being at right angles to each other.

4. In an artificial limb wrist and hand portions, said wrist portion including a rigid socket and said hand portion including a rigid skeleton frame, a bracket at the outer end of said socket having spaced apart aligned eyes, a pivot connecting the plate to the eyes at its opposite side edges, a yoke extending inwardly from the skeleton frame of the hand portion and straddling the plate, and a pivot connecting the yoke to the plate, said first and last named pivots being at right angles to each other, coil springs connecting

the socket to the frame and extending longitudinally of the wrist at the front, rear and sides thereof, a covering of yieldable material for said socket and wrist portion, and a covering for said hand portion integral with the first mentioned covering.

5. In an artificial hand, fingers of a flexible material and solid except for a relatively small bore therein to house actuating means therefor, and fingernails having raised central portions and flanges on rear and side edges, said fingers having recesses for removably receiving said flanges.

WILLIAM G. FARRAR, JR.
